US00D757814S

(12) **United States Design Patent**
Leighton et al.

(10) **Patent No.:** US D757,814 S
(45) **Date of Patent:** ** May 31, 2016

(54) **DISPLAY SCREEN OR PORTION THEREOF
WITH GRAPHICAL USER INTERFACE**

(71) Applicant: **3M INNOVATIVE PROPERTIES
COMPANY**, St. Paul, MN (US)

(72) Inventors: **Michael C. Leighton**, Excelsior, MN (US); **Pontus Axelsson**, Stockholm (SE); **Michael Rotstein**, Stockholm (SE); **Johan R. Andersson**, Stockholm (SE)

(73) Assignee: **3M INNOVATIVE PROPERTIES
COMPANY**, St. Paul, MN (US)

(**) Term: **14 Years**

(21) Appl. No.: **29/502,692**

(22) Filed: **Sep. 18, 2014**

(51) **LOC (10) Cl.** 14-04

(52) **U.S. Cl.**

USPC **D14/493**

(58) **Field of Classification Search**

USPC D14/485-495; D18/27; D19/6; D20/11, D20/23, 27, 29, 37

See application file for complete search history.

(57) **CLAIM**

The ornamental design for a display screen or portion thereof with graphical user interface, as shown and described.

DESCRIPTION

The sole FIGURE is a front view of a display screen or portion thereof with graphical user interface showing our new design. The broken line square showing the display screen in the sole FIGURE is included for the purpose of illustrating portions of the article and forms no part of the claimed design.
